[57] CLAIM

The ornamental design for a vehicle wheel, as shown and
described.

DESCRIPTION

FIG. 1 is a front perspective view of a vehicle wheel
showing my new design;

FIG. 2 is a front view of the wheel of FIG. 1;

FIG. 3 is a rear view of the wheel of FIG. 1;

FIG. 4 is a side view of the wheel of FIG. 1, with the
opposite side being a mirror image thereof; and,

FIG. 5 is a sectional view taken along line 5—5 of FIG. 2.
